UNITED STATES PATENT OFFICE.

DOLOR J. FAVREAU, OF ADAMS, MASSACHUSETTS.

FORK AND SPOON HOLDER.

1,151,452.

Specification of Letters Patent. Patented Aug. 24, 1915.

Application filed February 4, 1914. Serial No. 816,449.

To all whom it may concern:

Be it known that I, DOLOR J. FAVREAU, a citizen of the United States, residing at Adams, in the county of Berkshire and State 5 of Massachusetts, have invented new and useful Improvements in Fork and Spoon Holders, of which the following is a specification.

The invention relates to a spoon or fork support, and more particularly to the class 10 of spoon or fork support attachments for receptacles.

The primary object of the invention is the provision of a support of this character 15 wherein the same can be connected with a glass jar or a comparatively large necked bottle or other container so as to support a spoon, fork or the like when not being used, thereby avoiding the smearing of the 20 spoon, fork or the like with eatables or the dropping of the same into the contents of the jar, bottle or container.

Another object of the invention is the provision of a support of this character by 25 which a spoon, fork or the like may be rendered readily available in a thoroughly clean condition for use in serving the contents of a jar, bottle or other container.

A further object of the invention is the 30 provision of a support of this character wherein a spoon or fork can be conveniently held to avoid the necessity of the dropping of the same or of allowing it to remain in a bottle, jar or the like after the said spoon or 35 fork has been used for removing material or eatables therefrom, thereby avoiding the consequent disagreeableness of helping oneself to said material or eatables with a spoon or fork smeared or covered with such con- 40 tents.

A still further object of the invention is the provision of a support of this character which is simple in construction, readily and 45 easily adjusted, thoroughly reliable and efficient in its purpose, and inexpensive in manufacture.

With these and other objects in view, the invention consists in the construction, combination and arrangement of parts as will be 50 hereinafter fully described, illustrated in the accompanying drawing, and pointed out in the claims hereunto appended.

In the drawings, Figure 1 is a fragmentary side elevation of a container showing 55 the support constructed in accordance with the invention applied. Fig. 2 is a sectional

view on the line 5—5 of Fig. 1. Fig. 3 is a perspective view of the support removed. Fig. 4 is a perspective view of the band used with the device.

Similar reference characters indicate corresponding parts throughout the several views in the drawings.

Referring to the drawings in detail, A designates a portion of the body of a fruit 65 jar having a neck B, as usual, on which is hung the spoon, fork or like support herein-after fully described. The support comprises a resilient band 11 having in one end portion opposed spaced notches 12 cut in 70 from opposite longitudinal edges thereof to form laterally extending alternate tongues 13, while the opposite end of the said band 11 has cut therefrom out-bent ears 14 in which is pivoted a swinging latch or buckle 75 15, the same being provided with a T-shaped opening 16 through which is passed the notched end of the band, the latter being inserted in the wider end of the opening 16 so that its tongue will co-act with the smaller 80 end of the opening 16 for the locking of the ends of the band together by the swinging of the buckle 15 outwardly and inwardly toward the band, as shown in Fig. 5 of the drawings.

Mounted in the band 11 intermediate the 85 ends thereof is a resilient bearing strip 17 which is adapted to contact with the neck of the jar A when the band 11 encircles the said neck and is fastened thereto. The re- 90 silient bearing strip 17 serves to take up any looseness that may occur between the band 11 and jar A and frictionally hold the band against turning upon the neck of the container.

At the point of the resilient bearing strip 95 17 are fixed the limbs 19 for supporting the rectangular-shaped frame 19' having at one end a tray 20, and at its opposite end a yoke 21 so that a spoon or fork when not in use 100 may rest with its handle in the yoke and its other end in the tray, as shown in Fig. 1 of the drawings. It is of course understood that the support may be attached to the neck of the jar in any desirable manner, so that 105 the attaching means may be modified if desired to suit the taste or fancy of the manufacturer or to meet the requirements of various types of jars, bottles or the like.

In Fig. 4 there is shown a modified form 110 of band comprising a resilient strip 22 having cut therefrom a tongue 23 which is out-

bent, while formed in the said band 22 for a portion of its length are a series of openings 24 in any one of which the tongue 23 is adapted to engage for the fastening of 5 the band about the neck of a receptacle such as a jar, bottle or the like.

From the foregoing it is thought that the construction and manner of use of the device will be clearly understood, and therefore a more extended explanation has been 10 omitted.

What is claimed is:—

A support of the class described comprising a substantially rectangular shaped frame 15 formed from a single strand of wire having bent ends arranged in parallel relation to each other and at right angles to the frame

to form uprights, a tray fixed to one end of the frame, spaced ears upwardly struck from the opposite end of the frame to form a seat 20 for the handle end of an article when resting in the tray, a band, means on one end of the band for adjustably and detachably engaging the other end thereof for the securing of the same about the neck of a receptacle, and loops outstruck from the band to form sockets for the uprights of the frame.

In testimony whereof I affix my signature in presence of two witnesses.

DOLOR J. FAVREAU.
